UNITED STATES PATENT OFFICE

EMANUEL J. SHOEMAKER, OF KITCHENER, ONTARIO, CANADA, ASSIGNOR TO THE L. MCBRINE COMPANY, LIMITED, OF KITCHENER, ONTARIO, CANADA

HAND LUGGAGE

Application filed December 24, 1936. Serial No. 328,283.

This invention relates to hand luggage and more particularly to a means for packing garments so that they may be supported in upright position relative to the common manner in which luggage of this nature is carried.

The object of my invention is to provide hand luggage, having in combination therewith one or more garment supporting members carried relative to the hinged side of the upper or cover portion of the luggage.

A further object of my invention is to provide a supporting member which is hingedly mounted relative to the hinged side of the cover portion of the luggage and which supporting member carries a hanger rod over which the garments may be folded, which garments are further folded over the free end of the supporting member when the same is being moved to normal packed position in the said cover portion.

A further object of my invention is to provide hand luggage, having a plurality of garment supporting members, which are hingedly mounted on separate or common hinge connections relative to the hinged side of the cover portion of the luggage and which supporting members each carry a hanger rod over which garments may be folded, which garments are further folded over the respective free ends of each of said supporting members when said respective supporting members are being moved to their normal packed position in said cover portion.

A further object is to provide hand luggage, having therein a garment supporting member carried relative to the hinged side of the upper or cover portion of the luggage and a removable hanger rod carried adjacent the said hinged side in co-acting relationship to said supporting member.

A further object of my invention is to provide hand luggage, having therein one or more garment supporting members carried relative to the hinged side of the upper or cover portion of the luggage which supporting member or members are adapted to have carried thereon one or more removable hanger rods over which the garments may be folded, which garments are further folded over the free end of their respective support-

ing member as the same is being moved to normal packed position in said cover portion.

With the foregoing and other objects in view, as will appear as the description proceeds, the invention consists of the novel construction, combination and arrangement of co-operating elements as hereinafter more specifically set forth, claimed and shown in the accompanying drawings forming a part of the present application, in which:

Fig. 1 is a perspective view showing the embodiment of my invention, the supporting member being shown in lowered position ready to receive the hanger rod.

Fig. 2 is a similar view to Fig. 1, but showing a modified means of hingedly connecting the supporting member.

Fig. 3 illustrates the hanger rod, showing a garment in its primary folded position thereon.

Fig. 4 is a transverse sectional view, showing the embodiment of my invention with a garment in packed position.

Fig. 5 is a perspective view of a modified form of my invention.

Fig. 6 is an enlarged detail view, showing interconnecting means on which the supporting member hinges.

Fig. 7 is a perspective view of a further modified form of my invention.

Fig. 8 is a sectional view of a modified form, showing a plurality of supporting members hinged from common pivotal points.

Fig. 9 is a top plan view of a modified form of my invention, part of the body portion being broken away and the cover being shown in section.

Fig. 10 is a section view of a modified form of my invention wherein the supporting members are removably positioned in the cover.

Fig. 11 is a top plan view of a further modified form of my invention, the cover being thrown back and the supporting member being shown in lowered position.

Like numerals of reference designate corresponding parts throughout the different views.

8 is the body portion of the luggage, which may be of various sizes or shapes according to the particular purpose for which the luggage is to be used. This body portion may be provided with a partition 9, extending transversely or extending at right angles to that as shown in Fig. 1. 10 is a cover suitably hinged at its lower side to the upper edge of the rear side of the body portion 8 in any desired conventional manner. 11 are stay straps to limit the hinging of the cover 10 back a predetermined distance relative to the body portion 8.

12 is a supporting member, which may be made of a flat piece of material. To provide the desired efficiency and to eliminate weight to as great an extent as possible, I prefer to have the side portions cut away as illustrated. 14 illustrates L-shaped hinge plates, one portion of which is suitably riveted flat against the inner face of the lower side of the cover 10. The protruding side is provided with an opening. 15 are pins suitably riveted to the outer edges of the base portion 16 of the supporting member 12. These pins protrude outwardly and comprise a pivotal connection for the supporting member 12 in the openings formed in the protruding side of the L-shaped plates 14. I do not wish to be limited in the means or manner whereby the base portion 16 of the supporting member 12 is hingedly or pivotally connected in relationship to the cover 10. In Fig. 2, I have shown hinges 17, which provide an equivalent means for hinging the base portion 16 relative to the cover 10. In Fig. 5, I have shown guide plates 18 carried on the inner faces of the opposite sides forming the cover 10. These guide plates are provided with a longitudinal slot 19 in which the ends of the pins 20 may be moved. In this particular construction, the pins 20 are provided with grooves adjacent their free ends and the ends of the pins are positioned in locked relationship in their respective slots 19 of the guide plates 18 as shown in Fig. 6. In Fig. 7, I provide a bracket 21 which is pivotally connected as at 22 to the opposite sides of the cover 10. Pins 20 are carried by the outer ends of the base portion 16 and extend through suitable openings formed in the free ends of the bracket 21. If desired and found more convenient, the outer ends of these pins 20 may be of reduced proportion and, after being positioned in the free ends of the bracket 21, they may be headed.

In Fig. 8, I provide hinged plates similar to the L-shaped plates 14 as shown in Fig. 1. The supporting member 12^a has pins carried thereby similar to pins 15 shown in Fig. 1, so that this supporting member 12^a hinges in a similar manner to the supporting member 12 shown in Fig. 1. 12^b and 12^c are supporting members of similar construction to the supporting member 12, each being pro-

vided with its respective hanger rod 30. The supporting members 12^b and 12^c are provided at the opposite edges of their base portions 16 with hinged plates 32 and 33 respectively. The hinged plates 32 and 33 are each provided with an opening to permit the ends of the plates to fit over their respective pins 15 intermediate the L-shaped plate 14 and the edge of the base portion 16 of the supporting member 12^a. In Fig. 9, the hinging of the supporting member 12 is similar to that disclosed in Fig. 2. In Fig. 10, the hinging or pivoting of the end of the base portion of the supporting member 12 is done away with, but in packing luggage this end is rested against the inner face of the hinged side of the cover and the folding strip pivoted to position, which constitutes practically a similar action as would take place if the base portion was hingedly connected to the hinged side of the cover portion. In Fig. 11 the supporting member 12 is suitably hinged in any desired manner to the inner face of the hinged side of the cover portion. It will be noted that throughout the entire disclosure, I provide a construction wherein the base portion 16 of the supporting member 12 is hingedly or pivotally supported relative to the bottom of the cover when being positioned into packed relationship in the cover 10.

The folding strip 23 of the supporting member 12 may be provided with outwardly projecting lugs as at 24 to retain garments in proper position. Additional side strips 25 may be positioned on the flat faces of the folding strip adjacent the outer transverse edge thereof, so as to provide a rounded surface on which the garments will contact in rolled formation and eliminate the possibility of creasing. 26 are the retaining bands, each having one end permanently attached to the inner face of one side of the cover 10. The other ends are provided with hooks or fasteners 27, which may be fastened into suitable eyelets carried by the opposite side of the cover 10.

28 is a metal strap secured to the under side of the base portion 16, the ends of which are bent at right angles to the main portion thereof. These ends extend across the outer edges of the base portion 16 and protrude outwardly from the opposite face thereof as at 29. These protruding end portions are provided with openings. 30 is the hanger rod, having pins 31 protruding from the opposite ends thereof, which pins are adapted to be inserted into the openings formed in the protruding ends 29. The protruding ends 29 are so formed as to tension against the ends of the rod 30 when the pins are in normal position therein, yet are sufficiently flexible to allow insertion and removal of the rod 30.

In the disclosure Fig. 7, the partition 9

has formed on its upper edge a channel groove. This may be provided by means of an edging strip attached to and protruding up from each of the upper edges of the 5 partition.

Referring to Fig. 9, the supporting member 12 is hinged similar to that disclosed in Fig. 2. In this particular disclosure the hanger rod 30 is supported adjacent the 10 inner face of the hinged side of the cover portion so as to be in co-acting relationship relative to the base portion of the supporting member 12. 34 is a socket into which the pin 31 of the hanger rod will be fitted. At the 15 side of the cover I provide an engagement plate 35 having a suitable opening therein into which the pin, carried at the opposite end of the rod 30, will be inserted. This engagement plate 35 is formed from metal 20 which will provide spring tension to retain the rod in fixed position, yet will permit the removal of the same when desired.

Referring to Fig. 11 I provide a supporting member 12 which may be pivotally connected 25 relative to the inner face of the hinged side of the cover portion similar to the disclosure shown in Fig. 1, or it may be hingedly connected thereto similar to the disclosure shown in Fig. 2. The modification in this construction is in the hanger rod. The hanger rod 36 is preferably formed as a wire or light rod loop. A stud 37 is carried on the outer face of the base portion 16 of the supporting member 12. The hanger rod 36 is provided with 30 a looped or hooked portion and adapted to be engaged over the stud 37. The stud 37 may be of such proportion as to accommodate and support a plurality of hanger rods 36.

In packing hand luggage, as disclosed in 40 this application, the rod 30 will be transversely positioned intermediate the ends of the garment as illustrated in Fig. 3, which provides for the primary fold of the garment. When one or more garments are in this primary folded position on the rod 30, the rod, with the garments thereon, is laid on top of the supporting member 12, when the latter is in the position as shown in Fig. 1. The pins 31, carried by the rod 30, are then inserted in their respective openings in the protruding portions 29. The free end of the supporting member 12 is then hingedly moved to the position as shown in Fig. 4, the respective ends of the garment freely folding over the 45 folding strip 23 and hanging down over the outer face of the supporting member 12. The retaining bands 26 are then extended across over the garment to snuggly retain it in position and the hooks or snaps 27 are engaged in 50 the eyelets hereinbefore mentioned.

Referring to the modified form, Fig. 5, the supporting member 12 may be moved to position as shown in this drawing, the hanger rod 30 removed from the protruding ends 29, the 55 garments draped thereon as shown in Fig. 3,

the hanger rod returned to position, after which the supporting member will be dropped to the position as shown in dotted lines in Fig. 5, so that it can then be pivoted to the position as shown in Fig. 4. 70

Referring to Fig. 7, I provide a means for positioning the supporting member 12 away from the cover 10 so as to facilitate the placing of the garments in their proper position after which the supporting member is raised 75 slightly so as to lift the projecting ends 24 from their seated position in the channel on the upper edge of the partition 9. The base portion 16 is then moved to its normal position adjacent the lower side of the cover 10, 80 after which the free end of the supporting member 12 is hinged upwardly to a corresponding relative position to that as shown in Fig. 4.

Referring to Fig. 8, I provide practically 85 the same construction as shown in Fig. 1 other than providing for a plurality of supporting members pivoted from common centers. If desirous the base portion of each supporting member may be pivotally mounted or hinged 90 individually. By providing a plurality of supporting members such as shown as 12^a, 12^b, and 12^c, I disclose a construction whereby garments may be readily removed from any one of the plurality of supporting members 95 without disturbing the garments on any of the other of such supporting members.

Referring to Fig. 9, I provide a supporting member which may be pivotally or hingedly mounted relative to the inner face of the 100 hinged side of the cover portion. In this construction the roller is removably mounted adjacent the hinged side of the cover portion and in co-acting relative position to the base portion of the supporting member 12. After 105 the garments have been primarily folded over the hanger rod 30, as shown in Fig. 3, the rod will be positioned in the socket and engagement plate 34 and 35 respectively, the garments extending out over the supporting member 12. The supporting member 12 is then pivoted to its packed position, the garment receiving its secondary fold over the folding strip 23 in a similar manner to that as hereinbefore described. 110

Referring to Fig. 11, the garment is draped through the hanger rod 36 to provide the primary fold, the looped portion is then engaged over the stud 37, after which the supporting member 12 is pivoted to normal packed position, the garment receiving the secondary fold over the folding strip 23 in a manner similar to that previously described. 115

The foregoing specification and annexed drawings disclose the preferred embodiment 120 of my invention, but it is to be understood that minor changes may be resorted to in the commercial adaptation of my invention without departing from the scope of the invention as hereinafter claimed. 125

What I claim as new is:

1. Luggage, comprising a body portion; a cover portion hingedly connected to said body portion; a garment supporting member hingedly connected to the hinged side of said cover portion and a garment supporting means carried adjacent the hinged connection of said supporting member.
2. Luggage, comprising a body portion; a cover portion hingedly connected to said body portion; a garment supporting member hingedly connected to the hinged side of said cover portion and a garment supporting means removably carried adjacent the hinged connection of said supporting member.
3. Luggage, comprising a body portion; a cover portion hingedly connected to said body portion; a garment supporting member hingedly connected to the hinged side of said cover portion and a garment supporting means carried by the hinged side of said supporting member.
4. Luggage, comprising a body portion; a cover portion hingedly connected to said body portion; a garment supporting member hingedly connected to the hinged side of said cover portion and a garment supporting means removably carried by the hinged side of said supporting member.
5. Luggage, comprising a body portion; a cover portion hingedly connected to said body portion; a garment supporting member hingedly connected to the hinged side of said cover portion and a garment supporting means carried by said cover portion adjacent the hinged connection of said supporting member.
6. Luggage, comprising a body portion; a cover portion hingedly connected to said body portion; a garment supporting member hingedly connected to the hinged side of said cover portion and a garment supporting means removably carried by said cover portion adjacent the hinged connection of said supporting member.
7. Luggage, comprising a body portion; a cover portion hingedly connected to said body portion; a supporting member hingedly connected to the hinged side of said cover portion; a garment supporting means, on which a garment may be primarily folded, carried adjacent the hinged connection of said supporting member and a folding edge, formed on the free side of said supporting member, on which said garment may be secondarily folded.
8. Luggage, comprising a body portion; a cover portion hingedly connected to said body portion; a garment supporting member hingedly connected to the hinged side of said cover portion; a garment supporting means, on which a garment may be primarily folded, carried by the hinged side of said supporting member and a folding edge, formed on the free side of said supporting member, on which said garment may be secondarily folded.
9. Luggage, comprising a body portion; a cover portion hingedly connected to said body portion; a garment supporting member hingedly connected to the hinged side of said cover portion; a garment supporting means, on which a garment may be primarily folded, carried by said cover portion adjacent the hinged connection of said supporting member and a folding edge, formed on the free side of said supporting member, on which said garment may be secondarily folded.
10. Luggage, comprising a body portion; a cover portion hingedly connected to said body portion; a garment supporting member carried by the hinged side of said cover portion; said supporting member embodying a garment supporting means, on which garments may be primarily folded, and a folding edge, on which garments may be secondarily folded, and means for retaining said supporting member in packed position in said cover with said garments supported in parallel relationship to the normal carrying position of said luggage.
11. Luggage, comprising a body portion; a cover portion hingedly connected to said body portion; a garment supporting member hingedly connected to the hinged side of said cover portion and adapted to be hinged to a horizontal position over said body portion when being packed; a garment supporting means, on which garments may be primarily folded, removably carried by the hinged side of the supporting member and a folding edge, formed on the free side of said supporting member, on which said garments may be secondarily folded as said supporting member is moved to packed position in said cover.
12. Luggage, comprising a body portion; a cover portion hingedly connected to said body portion; a garment supporting member supported on the hinged side of said cover portion and primary and secondary folding means for supporting garments, on said supporting member in parallel relationship to the normal carrying position of said luggage.
13. Luggage, comprising a body portion; a cover portion hingedly connected to said body portion; a garment supporting means carried adjacent the hinged connection of said cover portion; a garment supporting member hingedly connected to the hinged side of said cover portion, a folding edge, formed on the free side of said member, and adapted to register adjacent the free side of said cover when said member is moved to packed position within the cover.
14. Luggage, comprising a body portion; a cover portion hingedly connected to said body portion; a supporting member, hing-

- edly connected to the hinged side of said cover portion; a means, adjacent the hinged end of said supporting member, on which garments may be primarily folded and a folding edge, formed on the free side of said supporting member, on which said garments may be secondarily folded.
15. Luggage comprising a body portion; a cover portion hingedly connected to said body portion; a garment supporting member adapted to have garments draped thereon and means, pivotally mounting the supporting member in said cover adjacent the hinged connection thereof, whereby said supporting member with garments draped thereon is movable to a position substantially closing the open top of said body portion and to packed position within said cover portion with its free edge extending to a position adjacent the free edge of said cover portion.
20. Luggage comprising a body portion; a cover portion hingedly connected to said body portion; a garment supporting member, substantially of H-shaped formation, upon which garments may be draped over one parallel portion of said H-shaped supporting member and means hingedly mounting said supporting member in said cover portion adjacent the hinged side thereof.
25. 17. Luggage comprising a body portion; a cover hingedly connected to said body portion; a garment supporting member, substantially of H-shaped formation, upon which garments may be draped over one parallel portion of said H-shaped supporting member; and the other parallel portion being hingedly connected to said cover portion adjacent the hinged connection between said body portion and said cover portion.
30. 18. Luggage, comprising a body portion; a cover portion hingedly connected to said body portion; a garment supporting member hingedly connected to the hinged side of said cover portion and adapted to be hinged to a horizontal position over said body portion to receive garments; a garment supporting means, on which garments may be primarily folded, removably carried adjacent the hinged end of said supporting member and a folding edge, formed on the free side of said supporting member, over which said garments may be secondarily folded as said supporting member is moved to packed position in said cover portion and means for retaining garments on said folding edge.
35. 19. Luggage; comprising a body portion; a cover portion hingedly connected to said body portion; a garment supporting member hingedly connected to the hinged side of said cover portion; a garment supporting means and means carried by said supporting member for removably attaching said garment supporting means adjacent said hinged side of said cover portion.
40. 20. Luggage; comprising a body portion; a cover portion having peripheral walls, one of which is hingedly connected to said body portion; a garment supporting member hingedly connected to said cover portion adjacent the hingedly connected wall thereof and a hanger rod, removably carried in brackets, carried by said cover portion adjacent the hingedly connected wall thereof.
45. 21. Luggage, comprising a body portion; a cover portion hingedly carried by said body portion; a garment supporting member having two spaced parallel portions, one of which is hingedly connected to said cover portion adjacent the hinged side thereof and the other of said portions designed as a folding edge for garments supported thereon and a garment supporting means removably carried by said hingedly connected portion of said supporting member.
50. 22. Luggage; comprising a body portion; a cover portion hingedly carried by said body portion; a garment supporting means, on which garments may be primarily folded, removably carried in said cover portion adjacent the hinged connection thereof; a garment supporting member having two parallel portions, one of which is hingedly connected to said cover portion adjacent the hinged side thereof and a folding edge formed on the other of said parallel portions on which garments may be secondarily folded.
55. 23. Luggage; comprising a body portion; a cover portion hingedly carried by said body portion; a garment supporting member hingedly mounted in said cover portion and on the hinged side thereof; a garment supporting means and means, on said garment supporting member, for removably supporting said garment supporting means adjacent the hinged connection of said member.
60. 24. Luggage, comprising a body portion; a cover portion hingedly carried by said body portion; a garment supporting member hingedly carried by the hinged side of said cover portion and means, on said garment supporting member, for removably supporting a hanger adjacent the hinged side of said cover portion.
65. 25. Luggage, comprising a body portion; a cover portion hingedly carried by said body portion; a garment supporting member hingedly carried in said luggage and a hanger rod removably carried adjacent the hinged connection of said body portion and said cover portion.
70. 26. Luggage, embodying a cover; a garment supporting member, one side of which is hingedly connected to one side of said cover and the other side adapted to swing to a position adjacent to the other side of said cover and a garment supporting means carried on the first mentioned side of said member.
75. 27. Luggage, embodying a cover; a gar-

ment supporting member, one side of which is hingedly connected to one side of said cover and the other side adapted to swing to a position adjacent to the other side of said cover and a garment supporting means in said cover adjacent the first mentioned side of said member.

28. A garment supporting means for use in combination with luggage, comprising a garment supporting member hingedly connected to a portion of said luggage and a garment supporting means carried on said member adjacent its hinged connection.

In testimony whereof, I affix my signature.

EMANUEL J. SHOEMAKER.
